(57) **CLAIM**

The ornamental design for a combined holder and handle for a fishing system, as shown and described.

DESCRIPTION

FIG. 1 is a side perspective view of a combined holder and handle for a fishing system according to the present design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The design is the overall shape of the combined holder and handle for a fishing system shown in the drawings. The portion shown in stippled lines is for illustrative purposes only and does not form part of the design.

The broken lines depict environment and are included for the purpose of illustrating only and form no part of the claimed design.
